UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,154,030.

Specification of Letters Patent. Patented Sept. 21, 1915.

Application filed June 19, 1911. Serial No. 634,147.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

10 My invention relates to electric switches.

It more especially relates to electric switches of the type known as three point pendant switches wherein the switch mechanism is arranged to control a plurality of circuits.

15 Among the objects of my invention is to provide an improved electric switch.

A further object of my invention is to provide an improved switch arranged to control a plurality of circuits which is of a very compact, simple and inexpensive construction and which is exceedingly efficient in service.

20 In the accompanying drawings I have illustrated one form which my invention may assume in practice. My invention is, however, not limited to this specific form and may assume various other forms.

25 In the views of the drawings: Figure 1 shows a central sectional view through the assembled switch. Fig. 2 shows a side elevation of one of the casing members. Fig. 3 shows a sectional view on line 3—3 of Fig. 2.

30 In these drawings I have illustrated a two part casing inclosing a push button snap switch mechanism and provided on its opposite sides with terminal contacts arranged to control a plurality of circuits, 35 certain of said terminal contacts on opposite sides of said switch mechanisms being electrically connected so that the same may be used in a three wire circuit.

35 The switch mechanism employed is preferably of the type described in my previously granted Patent No. 985,241, patented February 28, 1911. This switch mechanism includes a reciprocable cam member 1 of the conformation of a double frustum, positioned base to base, having flanges 2 on its reduced ends and carrying push buttons 3. A movable contactor 4, preferably of the type described in my co-pending application, Serial No. 628,782, filed May 22, 1911, is arranged to reciprocate on this cam mem-

ber and to house a garter spring 5 which acts to throw the contactor to one of the limits of its travel with a quick snap action when said cam member is actuated and when the spring has passed over the crest of the cam. This switch mechanism is mounted and inclosed in a two part casing 6 and 7 preferably formed of insulating material and preferably of a substantially rectangular cross section as illustrated in Fig. 1. 60 The parts of this casing are provided with oppositely extending perforations 8 and 9 arranged to permit the reciprocation of the push buttons through the same and not of a sufficient diameter to permit the reciprocation of the flanged cam member through the same. In order to receive the contactor and permit the same to reciprocate along the cam the two casing members are recessed 70 to form a central chamber 10. This chamber 10 preferably communicates with the perforations 9 by means of a recess 11 of greater diameter than the perforations 9 through which the cam member reciprocates. 75 In a preferred form, terminal contacts 12 are carried on the base member 6 while terminal contacts 13 are carried on the base member 7. These contacts are preferably seated in suitable recesses 16 and 17 near the top of the casing members and spaced 80 apart by septums 18 and 19. In a preferred form the terminal contacts are secured in these recesses by screws 20 and 21 extending through to the outside of the casing members and having their heads suitably sealed in recesses in the same. The shanks of these contact members are preferably narrower than the heads of the same and extend vertically downward through the chamber 10 and on opposite sides of the 85 same, the shanks of each pair being arranged on opposite sides of the chamber and the cam member 1. In a preferred form the side walls of the chamber 10 are recessed at 90 22 beneath and at the side of these shanks 100 so that the edges of the contactor 4 may pass freely along the sides of the terminal contacts. Also in a preferred form the bottom of the chamber 10 is provided with transversely extending recesses 23 on its opposite 105 sides so that the shanks may be readily placed in position in the casing and may be held in the same. If desired, the bottom of the chamber 10 may be recessed between these recesses 23. In order to secure the 110

parts of the casing together a screw 24 may be passed through suitable recesses in the septums 18 and 19 and be held in position by a tap 25. The head of the screw and the tap may be housed in suitable recesses in the outer surfaces of the casing members and these recesses may be sealed if desired. In order to effectually insulate the parts and prevent the arc showing through, as well as to exclude moisture from the switch mechanism, I may provide an insulating strip 26 fitted in registering grooves in the adjacent edges of the casings and extending substantially around the entire switch mechanism as illustrated in Fig. 2.

In a preferred form I provide the casings with a suitable cap. This cap preferably consists of a metallic cover 27 having a central perforation arranged to receive an insulating conductor bushing or basket 28 and provided with an insulating lining 29 crimped to the cover 27 and held in position in the same by indenting the cover as shown at 30. This cover is preferably secured to the top of the casing by screws 31 which are provided with threaded bushings 32 carried in or near the lower edge of the cap and are adapted to be moved into engagement with the walls of recesses 33 to hold the parts together. It is, of course, obvious that the conductors for the switch mechanism are brought in through the gasket 28 to the tops of the terminal members. In a preferred construction in order to permit the conductor to be more readily attached, I preferably slightly cut away the upper, inner edges of the casing members as illustrated in Fig. 1. In order that the switch may be connected to a three wire circuit I preferably connect one of the binding posts on each side of the switch mechanism by a conducting strip 34 which extends across the casing opposite and below the opening in the cap, so that a conductor may be readily attached to the terminal of the same. If desired one end of this conducting strip 34 may be riveted to one of the terminals on one of the parts of the base, while the other end may be attached to the binding screw on the opposite terminal. If desired this conducting strip may be slightly bowed as shown in Fig. 3 so that it will not interfere with the connection of the conductors to the terminals.

When it is desired to operate the switch all that is necessary to do is to push in one of the push buttons. As the push button is pushed in the garter spring travels up the slope of the cam and when it reaches the crest of the same throws the contactor to one of its extreme positions with a quick snap action. Since terminal contacts are provided at both of the limits of travel of the contactor, a circuit may be made at either limit of its travel. If desired, these circuits may be entirely independent or if desired,

they may be connected as in a three wire system with one of the conductors used as a common return. It is of course obvious that when the switch is connected in a three wire circuit one of the conductors is connected to the binding screw at the end of the conducting strip, while the other two conductors are connected to the binding screws on the opposite side of the base.

By my improved construction I have provided an exceedingly compact, simple and inexpensive three point switch which is of a rugged construction, employing a small number of parts which are well calculated to withstand long wear and service. Further, these parts are fully protected within the casing and the completed switch when assembled presents a very neat appearance.

While I have in this application described one specific form which my invention may assume in practice, I have chosen this form as a means of illustrating the principle of my invention and I accordingly do not wish to be limited to this specific form, but wish rather to include all of the forms which fall within the scope of my improvement.

What I claim as new and desire to secure by Letters Patent is as follows:—

1. In a multi-circuit electric switch, an insulating base having a substantially closed chamber therein, a snap switch mechanism carried in said base including a contactor movable across said chamber, and a plurality of terminal contacts mounted on said base at opposite sides of said chamber.

2. In a multi-circuit electric switch, an insulating base having a substantially closed rectangular chamber therein, a snap switch mechanism mounted within said chamber including a contactor reciprocable across the same, and a plurality of sets of parallel terminal contacts carried by said base at opposite ends of said chamber.

3. In an electric switch, an insulating base having a substantially closed chamber therein, a snap switch mechanism including a contactor within and movable across said chamber, a plurality of sets of contacts carried by said base on opposite sides of said chamber and extending without the same, and means without said chamber connecting certain of said opposite contacts.

4. In a pendent electric switch, a two-part insulating base having complementary recesses on its adjacent faces forming a substantially closed central chamber and an open end recess, a push-button operated switch mounted within said chamber and having its operating member extending through opposite ends thereof, a pair of terminal contacts carried by each of said base parts to be engaged by said switch mechanism in its opposite extreme positions, and means in said end recess connecting certain of said opposite contacts together.

5. In an electric switch, a divided insulating base having substantially flat adjacent faces, a snap switch mechanism inclosed between the parts of said base and having an operating member extending therethrough, and insulating means carried by and bridging the adjacent faces of said base substantially around said switch mechanism.
6. In an electric switch, a two-part insulating base, a snap switch mechanism inclosed therein, the adjacent faces of the parts of said base having complementary grooves about said switch mechanism, and an insulating strip interfitted within said grooves.
7. In an electric switch, a two-part insulating base, the adjacent faces of the parts of said base having complementary recesses and complementary grooves about said recesses, a snap switch mechanism inclosed in said recesses, and an insulating strip clamped in said grooves. 15

In witness whereof, I have hereunto subscribed my name in the presence of two witnesses.

CHARLES J. KLEIN.
